UNITED STATES PATENT OFFICE.

CLIFFORD C. MOSHER, OF LIMA, OHIO.

RUBBER MASTICATOR.

Application filed March 25, 1922. Serial No. 546,577.

To all whom it may concern:

Be it known that I, CLIFFORD C. MOSHER, a citizen of the United States, residing at Lima, in the county of Allen and State of Ohio, have invented new and useful Improvements in Rubber Masticators, of which the following is a specification.

This invention relates to machines for mixing and kneading plastic materials, more especially rubber compounds, and consists in certain improvements I have made to the machines covered by my Patents No. 1,371,046 of March 8, 1921, and No. 1,396,138 of Nov. 8, 1921, and known as rubber masticators.

The principal elements of the present machine are the same as those of the said earlier machines, and the present improvements are directed to the means for raising and lowering the frame and weight off and onto the trough neck, said means acting at the same time to tilt the trough, to the means for raising and lowering the weight in the frame, and to the form and structure 25 of the weight and the provisions for feeding the materials therethrough into the trough.

The improved machine is illustrated in the accompanying drawing, in which,

Fig. 1 is a plan view,

Fig. 2 is a vertical section from front to rear, and

Fig. 3 is a vertical section at right angles to Fig. 2.

In these views, the trough is marked 10, its upstanding rectangular neck 11, with external flange 12 at its top. On said flange fits the flange 14 of the frame or hopper-box 15, said flanges being provided with a 15 tongue-and-groove connection 13. The flange 14, it will be noticed, is external on the front and rear walls of the frame and internal on the side walls thereof. The top surfaces of the two internal flanges, see Fig. 13, constitute seats 16 for the correspondingly inclined shoulders 17 of the hopper weight 18 when it is in its lowest position. The portion of the hopper-weight below said shoulders fits slidably in the neck of the 20 trough, while the portion thereof above the shoulders fits slidably in the frame. Racks 20 slide in slots in the side walls of the hopper-weight and in guides 19 on the frame and are connected to the shoulders 17 of the 25 weight by bolts 22, passed through a cross-bar 21 and surrounded by a strong spring

23. The racks 20 are engaged by pinions 24, carried by shafts 25, driven through bevel gears 26 by a shaft 27, carrying loosely a worm-wheel 28, which can be connected to 60 said shaft by a clutch 29 and which is driven by a worm 31 on a short shaft 32, itself driven through worm gearing 33 by the motor 34. All this mechanism, from the pinions 24 to the motor 34, is carried on the 65 frame 15 and is raised and lowered with it by the four corner screws 35, journaled in uprights 36 of the machine frame and threaded into lugs 37 of the frame 15, said screws being simultaneously rotated by the 70 chain drive 38, actuated by the motor 39. It will be seen that, when the clutch 29 is engaged and the motor 34 rotates in one direction, the pinions 24 will force the racks, and through the springs 23 the weight 18, 75 downwardly, causing pressure on the material in the trough but permitting the weight to rise slightly in case of excess pressure. By disengaging the clutch the weight is left free to rise and fall and, by rotating the motor 34 in the opposite direction, the weight can be raised out of the trough neck. The extreme upward and downward travel of the weight is controlled by limit switches of a well known kind connected to 80 85 stop the motor.

The front wall of the trough has a feed opening provided with a hinged cover 40, through which the material to be treated is introduced. The front and rear inner walls 90 of the weight slope inwardly to a central longitudinal opening, constituting the outlet to the trough and closed by a valve 45. On each side of said opening, the bottom of the trough is concaved to form a cylindrical surface of substantially the same radius as the cylindrical inner surface of the trough, and the bottom of the valve 45 is shaped to continue said surfaces. Both the bottom of the valve and of the weight 95 are serrated, as indicated at 55, Fig. 2, to cause a tumbling or turning over movement of the material and prevent a mere sliding movement thereof. The means for actuating the valve 45 consists of a shaft 100 46, carrying arms 47, connected to the valve by links 48 of such length that the valve is locked in its closed position—and also in its raised position shown in dotted lines in Fig. 2—by reason of said arms and links 110 coming into alinement. Shaft 46 is driven through a chain 49 from short shaft 50, on

the squared end of which fits a crank handle 51, shown in dotted lines in Fig. 3. Fig. 2 also shows in dotted lines the uppermost position of the weight.

5 On the outside of the front wall of the weight I mount an oil reservoir 52, from which a valved pipe 53 leads through the bottom of the weight into the trough, while 10 54 represents a thermometer to indicate the temperature of the inside of the trough, it being connected thereto by a pipe 56. 57 represents a gage to indicate the amount of oil in the reservoir. 58 is a pressure-relief valve, connected to the trough through the 15 weight by a pipe 59 and manually controlled by the hand wheel and shaft 60.

The trough is tilted simultaneously with the raising of the frame 15, by means of nuts 61, travelling on the two rear screws 35 20 and connected to lugs 62 on the bottom of the trough by arms 63, pivoted to said nuts and lugs at their opposite ends.

The mode of operation of this machine will be obvious to those skilled in the art 25 from the above description, and need not be recapitulated here. I have omitted describing well known parts which constitute no feature of the present invention, for the sake of clearness and conciseness. I have 30 however marked the agitators 20 and their shafts 30, about the front one of which the trough tilts, as indicated by the dotted lines t in Fig. 2.

Having thus described my invention, what 35 I claim is:

1. In a mixing machine, the combination with the tiltable trough and a frame adapted to fit on the neck thereof during the operation, of means to raise said frame off said 40 neck and to simultaneously tilt the trough.

2. In a mixing machine, the combination with the tiltable trough and a frame adapted to fit on the neck thereof during the operation, of screws to raise and lower said frame 45 and connections from two of said screws to tilt the trough.

3. In a mixing machine, the combination with the tiltable trough and a frame adapted to fit on the neck thereof during the operation, of four screws engaging the corners of 50 said frame to raise and lower it, travelling nuts on two of said screws, and connections from said nuts to the trough whereby the latter is tilted as said frame is raised or lowered.

4. In a mixing machine, the combination with the tiltable trough and a frame adapted to fit on the neck thereof during the operation, of four fixed-axis screws threaded in 60 corner lugs on said frame, power means to rotate said screws, a nut on each of the two rear screws, lugs on the bottom of the trough, and arms connecting said nuts and lugs, whereby the trough is tilted simultaneously 65 with the raising or lowering of said frame.

5. In a mixing machine, the combination with the tiltable trough and a frame adapted to fit on the neck thereof during the operation, of a hopper-weight slidable in said frame and neck, power means to raise and 70 lower said hopper-weight, and other power means to raise said frame off said neck and to simultaneously tilt the trough.

6. In a mixing machine, the combination with the tiltable trough and a frame adapted 75 to fit on the neck thereof during the operation, of a hopper-weight slidable in said frame and neck, power means carried by said frame and operatively connected to said hopper-weight to raise and lower the same, a clutch 80 in said connections, and means to cushion the downward movement of said hopper-weight.

7. In a mixing machine, the combination with the tiltable trough and a frame adapted 85 to fit on the neck thereof during the operation, of a hopper-weight slidable in said frame and neck, racks on the side walls of said hopper-weight, a motor carried by said frame, and connections including a clutch 90 between said motor and racks.

8. In a mixing machine, the combination with the tiltable trough and a frame adapted to fit on the neck thereof during the operation, of a hopper-weight slidable in said 95 frame and neck, racks slidably mounted on the side walls of said hopper-weight, springs between the latter and said racks, a motor carried on said frame, pinions engaging said racks, and connections including a clutch 100 from said motor to said pinions.

9. In a mixing machine, the combination with the tiltable trough and a frame adapted to fit on the neck thereof during the operation, of a hopper-weight slidable in said 105 frame and neck, means carried by said frame to force said hopper-weight downwardly, springs to allow said hopper-weight to yield upwardly, and means to raise said frame and hopper-weight off said neck.

10. In a mixing machine, the combination with the trough and the mixing blades therein, of a hopper-weight slidable in the neck of 115 the trough and having a central feed opening in its bottom, the surface of said bottom being cylindrically concaved on each side of said opening, and a vertically movable valve to control said opening.

11. In a mixing machine, the combination with the trough and the mixing blades therein, of a hopper-weight slidable in the neck of 120 the trough and having a central feed opening in its bottom, the surface of said bottom on each side of said opening being cylindrically concaved and serrated, a valve to control said opening and manual means to actuate said valve.

12. In a mixing machine, the combination with the trough and the mixing blades therein, of a hopper-weight slidable in the neck of 130

- the trough and having a central longitudinal feed opening in its bottom, a valve controlling said opening, a shaft journalled in the walls of said hopper-weight, crank-arms on 5 said shaft, links connecting said arms to said valve, and manual means to rotate said shaft.
13. In a mixing machine, the combination with the mixing trough having an upstanding rectangular neck outwardly flanged at 10 its top, of a frame having an inturned flange at its bottom fitting on said neck flange, a hopper-weight the lower portion of which fits in said neck while its upper portion fits in said frame, the shoulder between said portions seating on the upper side of said inturned flange, means to raise and lower said hopper-weight in said frame and neck, and means to raise and lower said frame and hopper-weight off and onto said neck.
14. In a mixing machine, the combination with the trough, of a frame fitting on the neck thereof, a hopper-weight slidably fitting said frame and neck, the front and rear 25 inside walls of said hopper-weight sloping to an outlet opening in the bottom thereof, a feed opening at the top of said hopper-weight, a valve controlling the outlet opening, external means to control said valve manually, an oil reservoir on said hopper-weight, and a 30 valved pipe leading from said reservoir through the bottom of said hopper-weight into the trough.

15. A mixing machine comprising two parallel semi-cylindrical portions, a shaft journalled in the axis of each of said portions, a mixing blade on each shaft, means to drive said shaft in opposite directions, said trough having an upstanding rectangular neck, a weight sliding in said neck and having a central feed opening in its bottom, the 40 surface of the latter on each side of said opening forming a continuation of the surface of the adjacent semi-cylindrical portion of the trough and being serrated, and a valve in said opening the bottom of which likewise 45 forms continuations of said surfaces and is likewise serrated.

16. A mixing machine comprising a trough containing two agitator shafts about one of which said trough is tiltable, a hopper and closure mounted to fit on the neck of said trough, means to raise and lower said closure in said hopper, a motor carried by said hopper to actuate said means, power means to raise and lower said hopper off and onto said neck, and connections from said power means to said trough to tilt the latter.

In testimony whereof I have hereunto set my hand.

CLIFFORD C. MOSHER.
